S. W. Gibbs, of Albany, N. Y.
Assignee

Winne & Abel, of Albany aforesaid.
Letters Patent No. 941. Dated Sept 8th 1857.

The schedule referred to in these Letters Patent and making part of the same

To all whom it may concern:

Be it known that I, S. W. Gibbs, in the City of Albany, in the County of Albany, and State of New York, have invented or produced a new and original design for a Sad Iron Stove, and I do hereby declare that the following is a full and exact description thereof reference being had to the accompanying drawings and to the letters of reference marked theron.

Fig: A. represents the top of the said Sad Iron Stove, ornaments running around the outer edge on the moulding of said top, forming in combination an ornamental edge or moulding for the top of said Iron Stove. The ornaments are marked with the figure 1.

Figs: B and C. represent the front and end of said Stove ornaments running around the upper edge of the said front and end placed directly under or against the moulding of the said front and end, and also continued on down the front and end, also carried over the recesses with the addition of different shaped ornaments forming in combination an ornamental front and end
